COOLING MEANS FOR TURBINES

Ferdinand P. Sollinger, Paterson, N. J., assignor
to Curtiss-Wright Corporation, a corporation
of Delaware

Application September 11, 1946, Serial No. 696,287

7 Claims. (Cl. 253—39.15)

1

This invention relates to turbines and is particularly directed to the construction of the turbine rotor to provide for the flow of a cooling fluid in heat exchange relation therewith.

A conventional form of turbine rotor comprises a rotor disc portion having a cylindrical outer rim from which the turbine blades project radially, these blades being subjected to the heat of the hot working fluid of the turbine. Turbines, particularly gas turbines, are designed for operation at extremely high temperatures of the working fluid for maximum turbine efficiency. If the high temperature of the turbine working fluid is transmitted to the disc and hub of the turbine rotor, the safe operating stress of the turbine rotor is materially reduced. Accordingly, one of the problems encountered in the design and operation of a turbine is the provision of means for adequately cooling the turbine rotor.

An object of this invention is the provision of novel means permitting the flow of cooling air in heat exchange relation with the rim of the turbine wheel. Specifically, the invention comprises a pair of shelf-like spaced flanges projecting from a turbine blade shank, these flanges cooperating with similar flanges on the shanks of the adjacent turbine blades to provide passages between the shanks of each blade communicating with opposite ends of the turbine rotor. In addition, means are provided for circulating cooling air through these passages to cool the shank of the turbine blades thereby reducing the amount of heat conducted to the web of the turbine rotor. The radially outer flange of said spaced flanges cooperates with the corresponding flanges on the adjacent blades to form a continuous cylindrical surface forming the radially inner boundary of the turbine working fluid, the working portions of the turbine blades projecting radially outwardly from this surface.

A further object of this invention is the provision of a novel flange construction on each blade of a multi-stage turbine rotor whereby the flanges on the blades of one stage cooperate with the flanges on the blades of the adjacent stage to provide a continuous cylindrical surface forming the radially inner boundary of the turbine working fluid. A still further object of this invention comprises a turbine blade flange construction on a multi-stage turbine rotor whereby the flanges on the blades of each stage cooperate with the flanges on the blades of an adjacent stage to provide passages establishing communi-

2

cation between the remote ends of the multi-stage rotor through which a cooling fluid may flow.

Other objects of this invention will become apparent upon reading the annexed detailed description in connection with the drawing in which:

Figure 1 is an axial sectional view through a multi-stage turbine embodying the invention; 10 Figure 2, 3, 4 and 5 are sectional views taken along lines 2—2, 3—3, 4—4 and 5—5 respectively of Figure 1;

Figures 6 and 7 are perspective views of the first stage turbine blades looking in downstream and upstream directions respectively;

Figure 8 is a perspective view of the second stage turbine blades as viewed in an upstream direction;

Figure 9 is a side view partly in section of a 20 modified turbine blade; and

Figures 10, 11 and 12 are sectional views taken along lines 10—10, 11—11 and 12—12 respectively of Figure 9.

Referring first to Figure 1 to 8, a two-stage turbine rotor indicated at 10 comprises a pair of rotor members 12 and 14, each drivably connected to a shaft 16. The radially outer portions of the discs of the rotor members 12 and 14 are secured together by bolts 18 projecting through the rotor members and suitable bosses formed thereon. Blades 20 are welded to the outer rim of the turbine rotor member 12 as indicated at 22 and blades 24 are welded to the outer rim of the turbine rotor member 14 as indicated at 26. As illustrated in Figures 2 and 3 there is one blade 24 for each blade 20. The blades 20 comprise the first stage of the turbine rotor and the blades 24 comprise the second stage of the turbine rotor. Instead of welding the blades to the turbine rotor, they may be secured thereto by any other suitable means. Fixed blades 28 project radially inwardly between the first stage blades 20 and the second stage blades 24 from the turbine housing structure 29.

The turbine motive fluid is suitably directed into the blades 20 from a combustion chamber 31 by an annular nozzle construction 33 having fixed blades 32. After leaving the first stage blades 20, the turbine motive fluid is directed by 50 the fixed blades 28 into the second stage blades 24. From the second stage blades, the turbine motive fluid discharges into the exhaust duct 34. The relative disposition of the rotary blades 20 and 24 and stationary blades 28 is best seen in 55 Figure 2. This figure also discloses, by suitable

arrows, the approximate direction of the entrance and exit velocity of the working fluid relative to the blades 20 and 24 respectively and the direction of rotation of these blades.

Each blade 20 is provided with a flange or shelf-like construction 36 having a substantially rhomboid shape. The shank of each blade 20 is provided with a second flange or shelf-like construction 38 radially spaced from said first flange and also having a substantially rhomboid shape. Each flange 36 terminates adjacent to the corresponding flanges of the adjacent blades 20 to form a substantially continuous outer cylindrical surface from which the working portion of the blades 20 project. Similarly, each flange 38 terminates in substantially abutting relation with the corresponding flanges of the adjacent blades 20 whereby the flanges 36 and 38 provide passages 40 between the shanks of adjacent blades.

Each blade 24 is also provided with a pair of shelf-like flanges 42 and 44 having a spacing similar to the spacing of the flanges 36 and 38. Each flange 42 and 44 terminates adjacent to the corresponding flanges of the adjacent blades 24. Thus, the flanges 42 form a substantially continuous cylindrical surface from which the working portions of the blades 24 project. In addition, the flanges 42 of the second stage blades 24 form a smooth continuation of the flanges 36 of the first stage blades 20. As illustrated, the flanges 36 and 42 abut approximately midway of the fixed blades 28. In this way, the flanges 36 and 42 form a substantially continuous inner boundary for the turbine working fluid from one end to the other of the multi-stage turbine rotor 10. Similarly, the flanges 44 terminate adjacent the corresponding flanges of the adjacent blades 24 whereby the flanges 42 and 44 provide passages 46 between the shanks of the blades 24. Also, the flanges 44 of the second stage blades 24 form a continuation of the flanges 38 of the first stage blades 20 so as to align the passages 40 and 46 thereby providing continuous closed passages 40, 46 through the multi-stage rotor 10. The passages 40, 46 extend between the shanks of the rotor blades 20 and 24 from one end of the multi-stage rotor 10 to the other and each of these passages is completely closed by the turbine blade flanges and the adjacent blade shanks. Also, there is one such passage 40, 46 on each side of each pair of turbine rotor blades 20 and 24.

The passages 40, 46 permit the flow of cooling air therethrough, thereby cooling the turbine rotor blade shanks and reducing the heat conducted to the web of the turbine rotor. To facilitate the flow of air through the passages 40, 46, the upstream end of the turbine rotor member 12 is provided with a centrifugal impeller communicating with the passages 40, 46. For this purpose, a shroud 48 is secured to the rotor by the bolts 18 and conventional centrifugal blower or impeller blades 50 are formed rigid therewith. As illustrated, these blades 50 and the shroud 48 extend radially outwardly to the entrance of the passages 40, 46. With this arrangement, during turbine operation, cooling air is forced through the blade shank passages 40, 46 by the impeller 50 and from these passages the cooling air discharges into the exhaust duct 34 as hereinafter described.

The shank of each blade 20, radially inwardly of its working portion, is so formed between the

flanges 36 and 38 that this portion of the blade shank has substantially the same general outline as the radially inner end of the working portion of the blades 20. With this construction, the centrifugal forces acting on the working portions of the blades 20 are transmitted radially inwardly to the turbine rotor 12 without inducing bending stresses in the flanges 36 and 38. That is, the shank of the blades 20 between the flanges 36 and 38 is formed so as not to undercut any substantial portion of the inner end of the working portion of the blades 20. In this way, substantially each point on the blades 20 has a radially straight metallic connection through the shank of each blade with the rim on the turbine rotor 12. Accordingly, the flanges 36 and 38 do not transmit the centrifugal forces acting on the working portions of the blades 20 to the blade shanks and to the turbine rotor. As best seen in Figures 3 and 7, the shank of each blade 20 is extended downstream between its spaced flanges 36 and 38 by a web construction 51 hollowed out on its inner side to reduce its weight. As illustrated, each blade 20 also has recessed portions 52 and 54 radially inward of the flanges 38 for decreasing the weight of the blades. The recess portions 52 and 54 for the blades 20 also do not undercut the working portions of these blades.

The shank of each blade 24 is formed generally similar to the shank of the blades 20. That is, the shank of each blade 24 radially inward of its working portion and between its flanges 42 and 44 follows the general outline of the inner end of the working portion of the blade 24. The shank of each blade 24 is extended upstream between its flanges 42 and 44 by a web construction 55 similar to the web 51 of the blades 20. In addition, as illustrated, the shank extension 51 of each blade 20 abuts the corresponding extension 55 of a blade 24 whereby said shank extensions separate each passage 40, 46 from its corresponding adjacent passages.

The cooling air leaving the passages 40, 46 discharges into an annular diffuser passage 56. This annular diffuser passage is provided with diffuser vanes 58 to reduce the rotational velocity of the cooling air as it leaves turbine rotor 40, 46 thereby straightening out this flow before it discharges into the exhaust duct 34. Also, the effective cross sectional area of the discharge end of the diffuser passage 56 is designed so that the cooling air discharges into the exhaust duct 34 with substantially the same velocity as the adjacent velocity of the turbine exhaust fluid in the duct 34.

With the aforescribed construction, the spaced shelf-like flanges on the shanks of the turbine rotor blades, together with the blade shanks, form the walls of the passages 40, 46 extending from one end of the multi-stage turbine rotor 10 to the other. The spaced flanges on the turbine rotor blades and the blade shanks are extended across radially inwardly of the space occupied by the interposed fixed blades 28. In this way, the spaced flanges and turbine rotor blade shanks form continuous passage walls from the entrance to the exit end of the passages 40, 46 through the multi-stage turbine rotor. At the same time, the radially outer flanges on the turbine rotor blades form a continuous inner surface for the path of the turbine motive fluid across the multi-stage turbine rotor.

Although Figures 1-3 disclose a two-stage tur-

bine rotor, the invention is not so limited but may be applied to a turbine rotor having any number of stages of rotating blades.

Figures 9 to 12 disclose a modified blade construction for a single stage turbine, each blade 60 being secured to the rim of a turbine rotor 62, for example, by welding, as indicated at 64, or by any other suitable construction. Each blade 60 has a pair of radially spaced flanges 66 and 68 which terminate adjacent to corresponding flanges of the adjacent blade 60. The arrangement is such that the facing walls of the flanges 66 and 68 and the adjacent blade shanks form the walls of passages extending through the turbine rotor between the shanks of the blade 60. With this construction, a suitable cooling fluid can be caused to flow through these passages between the shanks of the turbine blades, e. g. by means of a blower as illustrated in Figure 1.

The passages between the shanks of the turbine blades may be made quite irregular by providing ribs or baffles 70, 71 and 72 on one side of the blade shank and abutting ribs or baffles 74, 75 and 76 on the adjacent blade shank. Except for baffle 72, these baffles only extend radially part way across the passages between the blade shanks so that the cooling fluid, in flowing through these passages, must follow the irregular paths around the baffles as indicated in Figure 9, thereby insuring intimate contact of the cooling fluid with the shanks of the blades 60. Obviously, if desired, similar baffles may be provided in the structure of Figures 1-8.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications.

I claim as my invention:

1. A turbine comprising a multi-stage turbine rotor having a first and a second stage of turbine blades secured thereto about its periphery, the blades of each stage being circumferentially spaced about said periphery and being axially spaced from the blades of the other stage, fixed turbine blades disposed between said first and second stage turbine rotor blades, and a shelf-like flange projecting laterally from the shanks of each of said turbine rotor blades, each said flange extending circumferentially into substantially abutting relation with the adjacent blades of its stage of turbine rotor blades and extending in a generally axial direction into substantially abutting relation with the flanges of said other stage of turbine rotor blades to form the inner boundary of the turbine motive fluid path between said blades and to form passages inwardly thereof between the shanks of adjacent circumferentially spaced turbine rotor blades for the flow of a cooling medium through said passages.

2. In combination, a multi-stage turbine rotor having a first and a second stage of turbine blades secured thereto about its periphery, the blades of each stage being circumferentially spaced about said periphery and being axially spaced from the blades of the other stage, fixed turbine blades disposed between said first and second stage turbine rotor blades, a shelf-like flange projecting laterally from the shanks of each of said turbine rotor blades, each said flange extending circumferentially into substantially abutting relation with the adjacent blades of its stage of turbine

rotor blades and extending in a generally axial direction into substantially abutting relation with the flanges of said other stage of turbine rotor blades to form the inner boundary of the turbine motive fluid path between said blades, said flanges being arranged to form passages inwardly thereof between the shanks of adjacent circumferentially spaced turbine rotor blades, and means for causing a cooling medium to flow through said passages.

3. In combination, a multi-stage turbine rotor having a first and a second stage of turbine blades secured thereto about its periphery, the blades of each stage being circumferentially spaced about said periphery and being axially spaced from the blades of the other stage, fixed turbine blades disposed between said first and second stage turbine rotor blades, a shelf-like flange projecting laterally from the shanks of each of said turbine rotor blades, each said flange extending circumferentially into substantially abutting relation with the adjacent turbine rotor blades of its stage and extending in a generally axial direction into substantially abutting relation with the flanges of said other stage of turbine rotor blades to form the inner boundary of the turbine motive fluid path between said blades, an exhaust duct into which said turbine motive fluid discharges, said flanges being arranged to form passages inwardly thereof between the shanks of adjacent circumferentially spaced turbine rotor blades, means for causing a cooling medium to flow through said blade shank passages, passage means establishing communication between said blade shank passages and said exhaust duct, said passage means having side walls inclined to the rotor axis to at least partially straighten out the flow of the cooling medium before said medium discharges into said exhaust duct.

4. A turbine comprising a multi-stage turbine rotor having a first and a second stage of turbine blades secured thereto about its periphery, the blades of each stage being circumferentially spaced about said periphery and being axially spaced from the blades of the other stage, fixed turbine blades disposed between said first and second stage turbine blades, a pair of radially spaced flanges projecting laterally from the shank of each of said turbine rotor blades, each pair of said flanges projecting circumferentially into substantially abutting relation with the corresponding flanges of the adjacent turbine rotor blades of its stage and projecting generally axially into substantially abutting relation with the corresponding flanges of the turbine rotor blades of the other stage, said flanges and the shanks of said turbine rotor blades forming the walls of passages through said multi-stage rotor between the shanks of adjacent circumferentially spaced turbine rotor blades for the flow of a cooling medium through said passages.

5. A turbine comprising a multi-stage turbine rotor having a first and a second stage of turbine blades secured thereto about its periphery, the blades of each stage being circumferentially spaced about said periphery and being axially spaced from the blades of the other stage, fixed turbine blades disposed between said first and second stage turbine blades, a pair of radially spaced flanges projecting laterally from the shank of each of said turbine rotor blades, each pair of said flanges projecting circumferentially into substantially abutting relation with the corresponding flanges of the adjacent turbine rotor blades of its stage, said pairs of flanges and the blade shank portions therebetween projecting

generally axially into substantially abutting relation with the shanks and corresponding flanges of the turbine rotor blades of the other stage, said flanges and the shanks of said turbine rotor blades forming the walls of individual passages extending through said multi-stage rotor from one end to the other between the shanks of adjacent circumferentially spaced turbine rotor blades for the flow of a cooling medium through said passages.

6. A turbine comprising a multi-stage turbine rotor having a first and a second stage of turbine blades secured thereto about its periphery, the blades of each stage being circumferentially spaced about said periphery and being axially spaced from the blades of the other stage, fixed turbine blades disposed between said first and second stage turbine blades, a pair of radially spaced flanges projecting laterally from the shank of each of said turbine rotor blades, each pair of said flanges projecting circumferentially into substantially abutting relation with the corresponding flanges of the adjacent turbine rotor blades of its stage, said pairs of flanges and the blade shank portions therebetween projecting generally axially into substantially abutting relation with the shanks and corresponding flanges of the turbine rotor blades of the other stage, said flanges and the shanks of said turbine rotor blades forming the walls of individual passages extending through said multi-stage rotor from one end to the other between the shanks of adjacent circumferentially spaced turbine rotor blades, the shank of each turbine rotor blade between its said flanges being formed so as not to undercut any substantial portion of the working portion of its blade for the flow of a cooling medium through said passages.

7. A turbine comprising a multi-stage turbine rotor having a first and a second stage of turbine blades secured thereto about its periphery, the blades of each stage being circumferentially spaced about said periphery and being axially spaced from the blades of the other stage, fixed

turbine blades disposed between said first and second stage turbine blades, a pair of radially spaced flanges projecting laterally from the shank of each of said turbine rotor blades, each pair of said flanges projecting circumferentially into substantially abutting relation with the corresponding flanges of the adjacent turbine rotor blades of its stage, said pairs of flanges and the blade shank portions therebetween projecting generally axially into substantially abutting relation with the shanks and corresponding flanges of the turbine rotor blades of the other stage, said flanges and the shanks of said turbine rotor blades forming the walls of individual passages extending through said multi-stage rotor from one end to the other between the shanks of adjacent circumferentially spaced turbine rotor blades, the portion of the shank of each turbine rotor blade between its said flanges radially inwardly of the working portion of its blade having a profile generally the same as the profile of the radially inner end of said working portion for the flow of a cooling medium through said passages.
